ATTORNEYS.

UNITED STATES PATENT OFFICE.

ARTHUR KERSHAW, OF PHILADELPHIA, PENNSYLVANIA, ASSIGNOR TO PHILADELPHIA METAL DRYING FORM COMPANY, OF PHILADELPHIA, PENNSYLVANIA, A CORPORATION OF DELAWARE.

HOSIERY-DRYING FORM.

Application filed March 19, 1927. Serial No. 176,613.

The ordinary hosiery drying form, whether of the hollow steam-heated or hot-air-heated type, or of the solid electrically heated type, is relatively wide and thin, like 5 the older wooden board, and more or less tapered at the edges. When the wet stocking is placed on the form, it assumes a shape thereon closely approximating that which it is desired it shall have when finished and 10 exposed for sale; that is, its wider dimension is between about the center of the front and the center of the back of the leg and between the top and bottom of the foot.

When full-fashioned stockings are 15 "boarded" on these forms, preparatory to drying, and during drying, there is a pronounced tendency toward distortion, the web in the heel of the stocking tending to slip or turn around the heel of the form toward the 20 leg; to obviate which requires much care and skill on the part of the operator.

The object of this invention is to so modify the form that this slippage cannot occur to any substantial extent. The object is accomplished by providing means, preferably an offset, in the bottom edge of the form, at about the junction of the heel and foot sections of the form, which will not obstruct the drawing of the stocking over the form, 30 but which, after the stocking has been properly positioned on the form, will, by its engagement with the web, offer sufficient resistance to prevent further slippage of the web at this point and thereby prevent the 35 turning movement of the stocking heel upon the heel of the form.

The invention will be better understood and its operation will be clearer by reference to the following description, supplemented 40 by the drawings, in which:—

Fig. 1 is a side elevation of a form embodying my invention and which is shown in the inverted position that it occupies when in use.

Fig. 2 is a cross-section through the form on the line 2—2 of Fig. 1.

The form comprises the leg portion *a*, the heel portion *b*, the foot portion *c* and the toe portion *d*. These portions of the form merge 50 one into another and form an integral whole; the division into sections being a convenient assumption to aid in the description.

In the usual seamless stocking the web

forming the heel is a continuation of the web of the rear of the stocking leg and the 55 courses of knitting extend parallel to the longitudinal axis of the body of the foot, while the knitting courses in the web forming the body of the foot extend around the foot. These two webs are united by a gore 60 or seam *x*, which extends, on each side of the foot, upward from the front of the bottom of the heel in a direction nearly parallel to the axis of the leg. It is extremely desirable that this gore shall occupy and maintain 65 this position during drying and finishing.

In the ordinary drying form, however, during boarding, the web tends to turn or twist about the heel in the direction of the arrow, thereby distorting the heel and swinging the gore *x* away from its normal position. This tendency is especially pronounced during the downward pull on the 70 stocking to stretch it tightly on the form.

In my invention this tendency is counteracted by providing means, preferably an offset in the bottom edge of the form at about the junction of the heel and foot, and on approximately the line which it is desired 75 that the gore *x* shall occupy when the stocking is being dried, which offset engages the stocking at or near, and usually at, the gore, when the stocking has been drawn onto the 80 form, and prevents further movement of the web in the direction of the arrow. Any further pull of the stocking will therefore operate on the web in a direction substantially 85 parallel to the direction of extension of the gore, instead of in a direction that tends 90 to turn it around the heel, thereby maintaining the stocking in perfect shape on the form, and so that, when stripped therefrom, it retains that shape.

The offset shown is both a projection and an indentation, but its operativeness is not dependent on any one specific shape. The offset shown is especially effective and comprises a shoulder *e* which faces toward the toe of the form and by engagement with the 100 gore acts as a stop to further movement of the web toward the heel of the form.

While the form shown is an internally steam heated drying form, the invention is not limited in its application to this specific 105 type of form.

Having now fully described my invention, what I claim and desire to protect by Letters Patent is:—

A hosiery drying form having leg, heel and foot portions and a shoulder having a sharp edge facing towards the toe at the junction of the heel and foot portions and

arranged to engage a stocking to prevent the heel of the stocking from slipping about the heel portion of the form during stretching. 10

In testimony of which invention, I have hereunto set my hand at Philadelphia, Pennsylvania, on this 12th day of March, 1927.

ARTHUR KERSHAW.
